COILER AND FEEDER ASSEMBLY FOR
REVERSING ROLLING MILLS

John F. Ferm, Midland, Pa., assignor to Crucible
Steel Company of America, New York, N. Y.,
a corporation of New Jersey

Application June 17, 1950, Serial No. 168,758

6 Claims. (Cl. 80—32)

1

This invention relates to the hot rolling of strip metal, and more particularly to apparatus for coiling and uncoiling upon a reel such metal which is undergoing hot rolling.

The invention in one aspect thereof is constituted by the combination with a rolling mill adapted for the rolling of material such as metal at a rolling temperature first in one direction and then in the other, and having a runout table and a pinch roll assembly positioned for operating upon material movable on said table, of a reel mounted above the runout table, the reel being provided with a slot for the reception of an extremity of the strip of material. A reel guide roll is mounted above the runout table and is positioned between the pinch roll assembly and the reel for guiding the strip as it moves between the table and reel. Means are provided for diverting material from the runout table upwardly toward the reel whereby an extremity of the strip is directed into the slot of the reel in preparation for winding the entire strip thereon. Such diverting means preferably comprises a section of the runout table which normally may be situated in the plane of such table. A stripper assembly, which also normally comprises a section of the runout table, is positioned adjacent said diverting means and is provided with a stripper element which is shiftable from its position as a section of said table to another position wherein it is in coil stripping relationship with the coil of strip material wound fully upon the reel. In such stripping position the stripper element in assisting the unwinding can guide the outermost loose extremity of the coil away from the reel, and in combination with said guide roll, can urge the unwinding strip material back toward the rolling mill. A down-guide element or out-reel guide assists in guiding the end of the strip material from the reel guide roll back to the pinch rolls. If desired, a hold-down roll may be employed and may be resiliently urged against the strip material while the latter is being wound upon the reel whereby the strip is wound in compact layers. When the strip is fully wound the hold-down roll prevents the whipping about of the loose end.

Various, further and more specific objects, features and advantages of the invention will clearly appear from the detailed description given below taken in connection with the accompanying drawings which form a part of this specification and illustrate, by way of example, preferred arrangements of apparatus for carrying out the invention. The invention consists in

2

such novel combinations of features as may be shown and described in connection with the device herein disclosed.

In the drawings:

5 Fig. 1 is a longitudinal section through a portion of a reversing hot strip mill, embodying one form of the present invention;

10 Fig. 2 is a plan view of the portion of the apparatus shown in Fig. 1 which includes the feeder, stepper and holddown roll assembly;

15 Fig. 3 is a view in sectional elevation as taken along line 3—3 of Fig. 2; while Fig. 4 is a view similar to Fig. 3 but showing the various components in different operative positions from those of Fig. 3;

Fig. 5 is a view in side elevation of a portion of the Fig. 2 assembly;

20 Fig. 6 is an enlarged sectional elevational detail view of the Fig. 2 assembly as taken along line 6—6 thereof; while Fig. 7 is a transverse sectional elevational detail view of the assembly shown in Fig. 6, as taken along line 7—7 thereof; and

25 Figs. 8 and 9 are fragmentary details, partly in section and with parts broken away of the Fig. 7 assembly, and illustrative of the different operative positions thereof.

Referring for the moment more particularly to Figs. 1 and 2, there is shown therein the right-hand portion of a reversing hot strip mill, embodying the above noted novel features of the present invention, the construction of the mill and its mode of operation being otherwise generally similar to that of U. S. Patent 1,977,214 to

30 A. P. Steckel. The mill, as shown in Figs. 1 and 2, comprises a four-high reducing mill stand shown generally at 10, consisting of reducing rolls 11 and 12, backing rolls 13, 14, mounted in a mill housing 15, in a conventional manner. The mill is also provided on either side of the mill stand 15 with runout or roll tables, as shown generally at 16, including driven table rolls as at 17, 18. Mounted above the table rolls is a strip coiler and furnace assembly, as shown generally at 20 and comprising a driven strip coiling drum 21, mounted within a furnace housing 22 of refractory material. The furnace is provided with air and fuel injection nozzles, as at 23 for maintaining the interior of the furnace at a desired operating temperature, as referred to more in detail hereinafter. Also mounted between the furnace housing 22 and the mill stand 15 is a pinch roll assembly shown generally at 24 and consisting of a low driven roll 25 and idling upper roll 26, which is elevatable and compressible by means

of a piston and cylinder assembly 27 in the manner described in said Steckel patent and requiring no further description herein.

In the operation of the mill as thus far described, a slab 28 of hot metal at a rolling temperature, is propelled back and forth between the reducing rolls 11 and 12, of the four-high mill 10 until it has been reduced to a thickness and extended in length sufficiently for coiling purposes. During this so-called flat rolling operation, the mill will be arranged as shown in Fig. 1, so that the slab 28 can be run out on the run-out tables 16, back and forth on either side of the mill. During this operation the driven table rolls 17, 18 serve to propel the slab away from the reducing mill 10 and return the same thereto, alternately feeding to the right and left through the mill on each pass. When, however, the slab has been reduced sufficiently in thickness and extended in length for coiling, the resulting strip is reeled up entirely on each pass on the coilers 21, mounted on each side of the roll stand, and in the manner generally indicated by the dotted line 29. In this way the entire strip can be heated in a desired manner in the furnace 22 during an operation of the hot rolling period.

The equipment required for effecting this coiling and also the uncoiling will now be described. The construction and operation of the coiling drum 21 is similar to that described in my co-pending application Serial No. 153,821, filed April 4, 1950. The coiling reel or drum consists in its essentials of a central blade member 35 of hollow, reinforced construction, and of substantially rectangular configuration in elevation and plan view and of roughly elliptical contour in transverse section, this central sleeve member being mounted on a water-cooled drive shaft 36. To the opposite sides of the central blade member 35, are respectively hinged, as at 37, 38, a pair of arcuately shaped peripheral blade members 39, 40, likewise of hollow, reinforced construction, all as described in my said co-pending application, each of which peripheral blade members 39 and 40 cooperates with the central blade member 35, to provide oppositely extending slots therebetween as at 41, 42, for receiving the leading edge of the hot rolled strip 29 to be coiled on the reel. The unhinged edges of the peripheral blades 39, 40 are secured in spaced relation to the central blade member 37 by means of straps as at 43, 44, extending therebetween and pin-connected thereto respectively.

The hot roll strip 29 is fed onto and off of the coiling reel 21, under a coiler guide roll 45, which also facilitates breaking and removal of scale formed on the strip. Roll 45 is reversibly power driven. For diverting the leading end of the hot rolled strip from the table rolls 17 onto the coiling reel 21, there is provided a grid-like diverting and elevating table 46, see Figs. 1, 2 and 3, this table being hingedly mounted at one end thereof as at 47, on a rocker shaft 48, the latter journaled to bearing members 49, 50, carried by a frame mounted on brackets 51, 52, which in turn are secured to a supporting structure 53. The elevating table 46 is also referred to as an elevating grid, elevating member or kick-up, also as an up-guide member or an in-reel guide. Such grid or table is journaled to the shaft 48, by means of spaced bearing hubs 54, 55 integral with the table, and adjacent the outer ends of the table as viewed in plan, Fig. 2. Also journaled to shaft 48 within the confines of the table bearing hubs 54, 55, is a strip receiving member or table 56, 75 mentioned in one position thereof, an active por-

consisting of a series of laterally spaced blades 57 integral, at one end of each, with an elongated bearing hub 58, the latter being journaled to shaft 48, within the confines of the spaced bearing hubs 54, 55 of the elevating table 46, as shown in Fig. 2. Table 56 is also referred to as a down-guide table, grid or member and also as an out-reel guide.

For raising and lowering the tables 46 and 56, during the appropriate intervals of the operating sequence as described below, there is provided a piston assembly 59, a cylinder 60 of which is pivotally mounted as at 61 upon trunnions 62, similar to a gun mount. A piston rod 63 of the assembly is pivoted at its upper end as at 64 to one end of a rocker arm 65, the opposite end of which is keyed to a shaft 66, at the approximate midpoint thereof as shown in Fig. 2. Also keyed to the opposite ends respectively of shaft 66 are a pair of rocker arms 67, 68, on the free ends of which are mounted pins as at 69, 70, extending into slots as at 71, Fig. 4, of link members 72, 73 (Fig. 2). The upper ends of the link members 72, 73 are in turn pin-connected as at 74, 75 to bosses as at 46a secured to the undersides of the table 46. The shaft 66 is journaled at its opposite ends respectively to bearing members 76, 76' mounted on the brackets 51, 52, above referred to.

Pin-connected to the underside of the elevating table 46, at intermediate points thereof, as at 77, 78, Figs. 2 and 4, are a pair of depending links 79, 80, the lower ends of which are slotted, as at 81, Fig. 4, for reception of pins as at 82 mounted on rocker arms 83, 84. These rocker arms are pivotally mounted at their midpoints as at 85, 86 on bracket members 87, 88 mounted on the frame structure 53. The opposite ends of the rocker arms 83, 84 are respectively pin-connected as at 89, 90, Figs. 2 and 4, to link members 91, 92, the opposite ends of which link members are in turn pin-connected to the underside of the strip receiving table or down-guide 56, as at 93, 94.

Mounted beneath the elevating table 46 and adjacent the piston and trunnion assembly 59, is a stripper assembly shown generally at 100, for stripping and feeding the trailing end of the strip coiled on the reel 21 back into the rolling mill as explained below. This stripper assembly comprises a stripper element 101 of roughly triangular configuration in end profile, and substantially rectangular in plan.

Referring particularly to Figs. 2 and 3, the stripper member 101 comprises an element which in one position thereof comprises a portion of the main table 46 and in another position thereof constitutes a guiding device for downwardly directing the unwinding strip of material back towards the rolling mill. Said stripper element 101 is made up of a pair of elongated portions 102, 103 which, if desired, may be metal castings and which are secured together at the extremities thereof in spaced relation by means of end plates 104, 105 as by means of bolts 106. Said end plates have respectively formed integral therewith bosses as at 107, 108 each of which is provided with a recess or is hollowed out as at 109, 110 for the purpose of journaling thereto the reduced opposite ends 111, 112 of a stripper roll 113.

Referring now to Fig. 3, it will be seen that the stripper roll 113, in combination with the elongated portions 102, 103, constitute, as above mentioned in one position thereof, an active por-

tion of the runout table 16 and the surfaces as at 102a, 103a comprise table surface members when in the position shown in this figure. In the position of the stripper element shown in Fig. 4, the table surface members 102a, 103a are in an inactive position, being shifted away from and out of the plane of said runout table, and the stripper surface members 103b are in an active position wherein they can assist in guiding the strip, when unwound, from the coil back into the mill. During the actual guiding of the temporarily loose end of the strip from the drum 21 back down into the mill, said stripper surface members 102b, 103b actively assist, as will appear more fully hereinafter, in so guiding the strip.

The mechanism for controlling the attitude of the stripper element 101 during its passage from the position of Fig. 3 to that shown in solid lines in Fig. 4, and during the return thereof, will now be described. The bosses 107, 108 have integral therewith outwardly projecting studs of reduced diameter as at 114, 115, respectively, which studs are journaled to slide blocks 116, 117 (Figs. 5 and 6). These slide blocks are in turn slidably mounted in slots 118, 119, respectively, of rocker arms 120, 121. The latter pair in turn are keyed at their lower ends (Figs. 2 and 3) to a shaft 122 which is journaled in bearing members 123, 124 mounted at the approximate center of said shaft on a suitable base member as at 125. The opposite ends of shaft 122 are also journaled in bearing members 126, 127, each having a rack or sector member, such as 128, 129 secured thereto. As shown more particularly in Fig. 2, the rocker arms 120, 121 are keyed to the extreme outer ends of the shaft 122. The racks 128, 129 mesh with pinions 130, 131, which latter in turn are keyed to stud shafts 132, 133. The studs in turn are journaled respectively to the rocker arms 120, 121. The studs project through the rocker arms and have secured to their outer ends, crank arms 134, 135, which are pin-connected as at 136, 137 to links 138, 139, the opposite ends of which latter are pin-connected as at 140, 141 to the slide blocks 116, 117, respectively.

Also centrally mounted upon the shaft 122 and keyed thereto is a rocker arm 142, which is actuated by a power cylinder device or piston assembly 143, the piston rod 144 of which is pin-connected to one end of the rocker arm, as at 145, the piston cylinder 146 being in turn swiveled to trunnions 147, as at 148. Mounted upon and secured to the shaft 122 within and adjacent to the gear sectors 128, 129 are a pair of levers 149, 150, the latter mounting on their opposite ends respectively stud shafts, as at 151, Fig. 3, to which rolls as at 152 are journaled. These rolls are adapted to engage and ride upon the lower plane surfaces, as at 153 of the links 72, 73 above described, this engagement occurring during a portion of the cycle of operations of the equipment as described hereinafter.

The stud shaft 115 integral with the boss 108 projects through the slide block 117 to which it is journaled, and has keyed to its outer end a lever 154, to the outer end of which is secured a stud shaft 155 mounting a cam roller 156. The cam roller 156 engages an elongated cam track 157 of a cam assembly 158 consisting of a vertical web 159, mounted upon and secured at its opposite ends to vertical angle members 160, 161 carried by supports 162, 163. The cam track 157 is welded or brazed to the web 159. The opposite ends of the cam track 157 are bridged by means

of a strap 164 bolted to the cam track as at 165, 166, to protect cam track and cam roller from mill scale and dirt.

Referring to Fig. 5, there is secured to the upper right-hand portion of the cam assembly web member 159, an outwardly projecting stud shaft 170, having pivotally mounted thereon a shunt track member 171, for returning the cam roll 156 to its farthest position to the right shown in this figure, as explained hereinafter. This shunt track member is substantially balanced by means of an appropriate weight 172 adjustably secured by means of a bolt 173 to a balancing arm 174 integral with the track member 171. The shunt track member 171 has the angular or offset configuration, viewed in plan, as shown in Fig. 2. The left or lower extremity 175 of member 171 (Fig. 2) is in substantial alignment with the cam track or face 157, while the right or upper portion 176 of member 171 is offset to clear the path of a weighted return member 177 for the cam roll 156. This return member 177 is of rectangular configuration viewed in elevation as shown in Fig. 5 and is pivoted to a stud shaft 178, which latter in turn is mounted upon the cam web 159. A lower arm 179 of member 177 is adjustably weighted as at 180 with a balancing weight, while an upper arm 181 thereof is normally held against a lug member 182, by the weighted action of the lower member, to provide a slight clearance between arm 181 of the return member and the offset portion 176 of the shunt track member 171, as shown at 183. An extreme upper surface 184 of arm 181 is of arcuate configuration to receive and temporarily retain the cam roll while it is being returned to the position shown in Fig. 5, as explained in detail hereinafter. Referring to Fig. 7 in conjunction with Fig. 5, the upper edge 184 of the arm 181 of the return member 177 is transversely offset in the manner shown at 184a in Fig. 7 to receive the outer end of the cam roller 156 on its return while a cut-out opening 185 provides a path for the cam roller 156 to pass under portion 184a on its initial traverse towards the left along the cam 157 from the right extreme position shown in Fig. 5.

Referring to Fig. 1, a hold-down roll assembly shown generally at 190 is provided for reeling the strip 29 in compact layers on the coiling reel 21 and controlling the free end of the strip. This assembly comprises a hold-down roll 191 of hollow construction journaled at its opposite ends onto stud shafts 192, the latter in turn being secured to arms as at 193. The arms 193 are of roughly angular configuration and are mounted on their ends opposite to the roll 191 on a shaft 194, keyed thereto. Also keyed to shaft 194 is one end of a lever arm 195, the opposite end of which is pivotally connected as at 196 to a piston arm 197 actuated by a cylinder 198, the cylinder being swiveled as at 199 to trunnions 200 mounted on a supporting structure 201.

In operation, in hot reducing a slab of hot metal first into an elongated plate and thence into relatively thin strip material, a slab of metal at an appropriate rolling temperature is delivered upon the table rolls 18. The apparatus is initially as shown in Fig. 1, in which condition the slab of metal upon the table rolls 18 is propelled thence onto the table rolls 17, and then through the reducing rolls 11 and 12 of the mill stand 10, and thereafter onto the corresponding table rolls on the opposite side of the mill stand. The slab thus is rolled alternately back and forth through the mill until it is reduced to a thickness suitable for

coiling. The plate indicated at 28 constitutes a showing of the material at an intermediate rolling stage while it is being rolled flat and prior to coiling. When the plate has been reduced to a sufficient thinness and length for coiling, the coiling drum or reel 21, which may be rotating slowly, is arrested by suitable control means (not shown) in the position shown in Fig. 3 wherein one of the slots, as at 41, is positioned to receive an advancing extremity of the strip material 29. It is not necessary to employ the pinch rolls 25, 26 while the material is in relatively thick slab form because the reducing rolls 11 and 12 are adequate for advancing the slab. However, when the material becomes relatively thinner, the pinch rolls may be employed for assisting in thrusting the material back and forth. The upper pinch roll, as at 26 of the pinch roll assembly 24, accordingly may be elevated, if desired, but is thrust downwardly by means of the piston assembly 27 against the lower pinch roll 25 when it is desired to actuate such assembly drivably to feed the strip therethrough. After the drum 21 has been positioned, as shown in Fig. 3, and the coilable strip material is approaching same, moving to the right as viewed in this figure and in Fig. 1, the kick-up or up-guide member 46 is raised to the position shown in Fig. 3 whereby the leading edge of the strip 29, being propelled to the right by said pinch roll, is moved up the now inclined surface of the kick-up into the slot 41 of the drum or reel 21. When such leading edge has penetrated into the slot to a desired depth, the coiling reel promptly is set into motion and driven in the direction of the arrow (Fig. 3) whereby the strip is sharply bent over lip 210 of the peripheral blade 39 of said reel and thus locked in engagement therewith. As the reel continues to rotate, the strip 29 will be shifted to the position shown at 29a whereby the upper surface thereof engages the roll 45. When the kick-up or up-guide element is raised from the position shown in broken lines (Fig. 3) to that shown in solid lines by means of the power cylinder or piston assembly 59, the down-guide table or grid 56 is not affected and does not change in position, by virtue of the slot 81 (Fig. 4), which permits of such raising of the grid 46 without affecting the position of the grid 56 via the linkage 83, 91. As the winding proceeds, the strip will be rapidly wound in successive layers onto the reel 21 in the manner shown in Fig. 1. When the strip material is thin, there is a tendency for it to buckle as it issues from the mill 10 or from the pinch roll assembly 24. The rapid taking up of such strip material by the reel eliminates the dangers of such buckling and such reel here employed is so adapted for taking up the strip material. In order to assure that the coil will be wound tightly onto the reel, the hold-down roll 191, which is normally in the position shown at 191a (Fig. 1), is actuated by means of the piston lever and arm assembly 193-198, inclusive, to advance such roll to the position shown in broken lines whereby it engages and is urged against the strip being wound upon the reel 21. The reeling of the strip material can be continued without regard to the position of the trailing extremity of such material with respect to the adjacent pinch rolls as at 25, 26, that is, it is unnecessary for the operator of the mill carefully to watch the position of the trailing or outer strip extremity and to arrest the mill before such extremity is free of such pinch rolls. Thus reeling of the strip material can be continued by means of the present invention until the trailing edge

of the strip has cleared the pinch rolls 25, 26 and also the guide roll 45, and thus has been completely wound upon the reel 21. Consequently, the entire strip is subjected to the action of the pinch rolls 25, 26. That is, the trailing or outermost extremity of the strip is subjected to the action of the pinch rolls next adjacent to the reel 21. A relatively enlarged portion at each extremity of the strip thus is avoided which in the past has occurred because of the necessity to keep an outermost strip extremity between such pinch rolls for the purpose of unwinding the strip on the reel. Also the entire strip when thus wound upon the reel in the furnace 22 is subjected to the furnace temperature which normally would not be the case if it were necessary to permit the trailing or outer strip extremity to remain between the next adjacent pinch rolls 25, 26. At this stage of the reeling, the hold-down roll 191, engaging the outer surface of the coil, prevents the free end thereof from whipping loosely. As soon as the coiling of the strip material upon the reel 21 has begun and the strip has passed over and against the main guide roll 45, it is no longer necessary to maintain the kick-up or in-reel guide 46 in the raised position as shown in solid lines in Fig. 3. Consequently, at this stage of the operation said kick-up can be lowered by relieving the pressure of the actuating fluid medium in the power cylinder assembly 53 whereby said kick-up is lowered under gravity. Such lowering may be cushioned by conventional dashpot means embodied in the cylinder 50. The grid 46 is thus lowered until it assumes the position shown in broken lines in Fig. 3, such lowering being arrested by the limit-stop action of the lower faces 153 of link members 72, 73 engaging the rolls 152, the latter being mounted upon the arms 149, 150 and being temporarily rigidly held in the position shown in Fig. 3.

At this stage of the operation it is desirable to advance the stripper element 101 from the position shown in Fig. 3, wherein it forms a portion of the runout table, to a stripping position, which position it may assume somewhat in advance of the time when it is actually needed. The stripper element 101 is advanced by actuating the power cylinder assembly 143 which advances the piston rod 144 and with it the rocker arms 120, 121 mounting the stripper element 101 and the other pertinent parts, whereby such element may be moved from the position shown in Fig. 3 to any one of the positions as shown in broken lines in Figs. 4 and 5 as desired by the operator controlling the apparatus. As the piston 144 advances to the left, as viewed in Fig. 4, the gears 130 and 131 will be rotated counterclockwise by their meshing engagement with their respective stationary segment gears 127, 128 and thus, through the action of the crank and lever members 134, 138, will displace the side blocks 116, 117 first toward and then away from the shaft 122 upon which the rocker arms 120, 121 are mounted. Thus the axis of the stripper roll 113 is guided along the path indicated by the broken line 211 (Figs. 4 and 5). Thus the stripper element is caused slightly to move away from the reel 21 at a desired portion of the path thereof in order to avoid such reel and the coils of strip material thereupon. Such path of the axis of the roll 113 is also desirable in view of the progressive changes in attitude of the stripper portions 102, 103 which occur as such element proceeds to the left from its position as viewed in Fig. 3. Such changes in attitude of the stripper element are, of course,

effected in order to present the stripper surface members 102, 103 in proper position for guiding the outer free end or extremity of the strip of coiled material back into the mill via the guide roll 45 with the assistance of the stripper roll 113 and the down-guide element or grid 56, as will be explained further hereinafter. Such changes in attitude are effected as follows: the cam roll 156, which is mounted on the arm 154, the latter being secured to stud shaft 115, will traverse the cam face 157 along the path indicated by the circles shown in broken lines, the path being also shown by the arrows 213 in Fig. 5. The portion 103 of the stripper element, being the larger, is substantially heavier than the portion 102 and thus tends to rotate members 102, 103 clockwise as viewed in Fig. 5. Hence the cam roll 156 will be held in continuous engagement with the cam face 157 as such roll moves toward the left (Fig. 5) thereby causing the stripper portions 102, 103 to assume the successive angular positions shown at 214, 215 and 216 (Fig. 4) during the advance of such stripper from its initial to its final positions. The cam roll 156 thus moves from its position farthest to the right, as viewed in Fig. 5, along the cam face 157 and beneath the portion 175 of the shunt track member 171, thereby elevating the latter slightly to the position shown in broken lines in Fig. 5. When such cam roll 156 moves from beneath such portion 175, the latter, under the influence of gravity, drops counterclockwise to its initial position as shown in solid lines in this figure.

If desired, the stripper element, during the winding of the coil upon the reel 21, may be moved to position 216 (Figs. 4 and 5) wherein the stripper roll 113 urges the strip 29 between the latter and the main guide roll 45. Or, if desired, the stripper element may be held in an intermediate position wherein the stripper wedge or nose abuts the coil of strip material in the manner indicated at 217 (Fig. 5). Of course, if the stripper element is moved to position 216 during the winding or coiling of the strip material, it must be withdrawn to a stripping position when it is desired to unwind the coil of material and feed same back into the mill. When the strip is wound upon the coil 21 and it is desired to feed the strip back into the mill, the coil 21 should be arrested in rotation in such a manner that the outer end 218 of the strip hangs downwardly, as shown in Fig. 5, far enough so that it may be pushed to the left as viewed in this figure by means of the stripper element and grasped in the bite between the rollers 45 and 113. For this purpose the stripper element should be retracted, for example, to a position as at 217a, or, if desired, a position further to the right (Fig. 5). Substantially simultaneous with the arresting of the rotation of the coil 21, the roller 191 should be brought to bear against the coil of the strip material to prevent it from unwinding and hindering the movement of the region of the strip end 218 into the bite of said rollers 45 and 113.

The down-guide table or grid 56 is elevated to the position shown in Fig. 4 automatically as a result of the lowering of the limit-stop rolls 152 away from the surface 153 of the links 72, 73. Such lowering takes place, of course, well in advance of the shifting of the stripper element into the position 216. Consequently, when the unwinding of the coil of strip material occurs, the grid 56 is in a raised position and, in combination with the stripper surface member 103b,

is capable of guiding the now returning strip material back between the pinch rolls 25, 26 and thence toward the reducing rolls 11, 12. This cycle of operation is repeated until the strip is reduced to the desired final thickness.

Either the guide roll 45 or the stripper roll 113 may be reversably drivable by suitable power means in order to assist in the elimination of buckling of the strip material as it is unwound from the reel 21. For example, when the reel 21 is reversed in rotation for the unwinding of the coiled strip material thereon, the stripper element guides away from the coil the free extremity thereof as at 218 and into a position between the rolls 45 and 113 whereupon the latter may be urged strongly towards and against the roll 45 with the strip material pressed therebetween. The pulling off or unwinding of the strip material thus may be materially assisted by so driving, for example, the roll 45 by suitable power means whereby such buckling between the reel and said pair of rolls is eliminated. Of course, when the strip of material is grasped between the pinch rolls 25 and 26, and the latter are run at adequate speed, the danger of such buckling between the reel and the rolls 45, 113 is eliminated and then it is desirable to separate the roll 113 from guide roll 45.

After the strip material has been grasped by the pinch rolls 25, 26 for feeding back into the mill the stripper element 101 may be returned to its initial position indicated at 214 (Fig. 4). During the return of the stripper element to its initial position from position 216, the cam roll 156 will roll upon the shunt track member 171 to the position 156a wherein it engages the extreme upper surface 184 of the pivoted arm 181, the latter being shiftable angularly clockwise to carry the cam roll back to its farthest position to the right (Fig. 5), such carrying of the roll being over the cut-out opening 185 (Fig. 7).

If desired, automatic means may be provided for starting the rotation of the drum 21 after the end of the strip material has penetrated into one of the slots such as 41. For example, a beam of light may be directed across said slot against a photo-electric cell, such beam being interruptible by the end of the strip when it enters the slot. Such interruption can actuate a switching device for energizing the power means for driving the reel, thereby setting the drum 21 in motion promptly and rapidly in order to take up the strip of material without delay and thus to avoid any buckling therein.

While the invention has been described with respect to certain preferred examples which have given satisfactory results, it will be understood by those skilled in the art, after understanding the invention, that various changes and modifications may be made without departing from the spirit and scope of the invention and it is intended, therefore, in the appended claims to cover all such changes and modifications.

What is claimed is:

1. In a coiler and feeder apparatus for metal strip, the combination of: a runout table; a pinch roll assembly positioned for operating upon material movable on said runout table; a coiler drum mounted above said runout table, said drum being provided with a slot for the reception of an end of such material; a coiler guide roll above said runout table and positioned between said pinch roll assembly and said coiler drum; means for diverting material from said runout table upwardly toward said coiler drum whereby an ex-

tremity of such material is directable into the slot of such drum; a stripper assembly positioned adjacent said diverting means and having a stripper element associated therewith, the latter element being mounted for movement from a primary position in which it comprises a portion of said runout table, to a secondary position in which it is positioned sufficiently close to the coil of material upon said drum for guiding the outermost extremity thereof away from the drum and between said stripper element and guide roll; and means for guiding material from between said stripper element and coiler guide roll towards said pinch roll assembly.

2. In a coiler and feeder device for metal strip, the combination of: a runout table; a slotted reel mounted above the runout table and having at least one slot therein adapted for receiving the extremity of such strip material; means for diverting such strip material from the runout table upwardly into a slot of said reel; a reel guide roll mounted above the runout table and adjacent the reel for guiding material onto said reel; a stripper element normally positioned in the plane of the runout table and mounted for movement from the latter position to a stripping position adjacent the strip material coiled upon said reel for guiding the outer extremity of such coiled strip material away from said reel, said stripper element being provided with a stripper roll which is urgeable against said reel guide roll with the strip of material therebetween; and a down-guide element operable in timed relation to the movement of said stripper element toward said reel guide roll for guiding the strip of material away from said reel, one of said rolls being power driven.

3. In a coiler and feeder apparatus for strip material, the combination of: a table, a slotted drum mounted above said table and adapted for receiving the extremity of a strip of material and for coiling same thereabout, a coiler guide roll positioned for guiding material from said table onto said drum during the coiling of the latter thereabouts and from the drum onto the table during the uncoiling of such material; an up-guide element positionable normally in the plane of said table but shiftable to a position for guiding an extremity of a strip of material from the table into a slot in said drum whereby such material may be coiled thereabout in response to rotation of said drum; a stripper element including a stripper roll situated between a pair of table surface members and also situated between a pair of stripper surface members, said surface members converging to form a stripper wedge, means for shifting said stripper element from a primary position wherein said table surface members are substantially in the plane of said table, to a secondary position wherein said stripper wedge is held adjacent the outer surface of the material coiled upon said drum for guiding the outer extremity of said coiled material away from the drum, and also being shiftable to a third position wherein said strip of coiled material is pressed between said coiler guide roll and said stripper roll; and a down-guide element movable into register with one of said stripper surface members of said stripper element in timed relation with the movement of the latter into said third position whereby the strip material is guided down onto said table.

4. A coiling and uncoiling mechanism for strip material having in combination a table; a slotted reel mounted above said table and having at least

one slot therein adapted for receiving the extremity of such strip, an angularly shiftable up-guide member mounted beneath said reel and normally positioned in the plane of such table, means for angularly shifting said up-guide member from a position in the plane of the table to an up-guide position for directing such strip into the slot in said reel; a reel guide roll mounted above the runout table and adjacent said reel for guiding such strip from and to said reel; a stripper element having a stripper roll situated between a pair of table surface elements and a pair of stripper surface elements, said pairs of elements converging to form a stripper wedge, said stripper element normally being positioned with the table surface elements in the plane of the table and the stripper surface elements therebeneath, means for shifting said stripper element from said first position toward said guide roll and means simultaneously operable with said last-named means for angularly shifting said table surface and stripper surface elements to a preselected position whereby the latter elements are positioned for stripping away a free outer extremity of such strip from said reel, said stripper element being shiftable by said shifting means to a position wherein said stripper roll is urged against said guide roll with the strip therebetween; a down-guide element for guiding the strip which is being unwound from said reel, said down-guide element being shiftable from a position normally at or below the plane of the table to a position in alignment with said stripper surface elements for guiding the strip which is being unwound from said reel.

5. In a coiler and feeder apparatus for strip material, a runout table; a slotted reel mounted above the runout table and having a slot adapted for receiving the extremity of a strip of material; means for diverting strip material from the runout table upwardly into a slot of said reel; a reel guide roll mounted above the runout table for guiding material from the pinch rolls onto the reel; a stripper element having a stripper roll mounted between a pair of stripper surface elements, said stripper element being positionable closely adjacent the material coiled upon said slotted reel for guiding away from such reel a free outer extremity of strip material after the latter has been wound fully thereupon, said stripper element also being positionable with the roll thereof against said reel guide roll with the strip material therebetween; and a down-guide element positioned normally out of the path of material moving upon the runout table, said down-guide element being shiftable into alignment with the stripper surface elements of said stripper element for guiding strip material being unwound from said reel.

6. In a coiler and feeder apparatus for strip material, the combination of: a runout table; a slotted roll mounted above the runout table and adapted for receiving the extremity of a strip of material; a kick-up for diverting strip material from the runout table upwardly into the slot of said reel; a guide roll also mounted above the runout table and adjacent to the reel for guiding material to and from said reel; a stripper element for stripping away from said reel the outer free extremity of strip material coiled thereupon, said stripper element including a stripper roll; and a down-guide element movable into aligned position with said stripper element for guiding such free end of strip material away from said reel, said down-guide ele-

ments normally being positioned out of the path of the material moving upon the runout table but being movable to said position for guiding the strip material in cooperation with said guide means, said guide and stripper rolls being urgeable towards one another for grasping the strip material therebetween, one of said last-mentioned two rolls being power driven thereby to move the strip of material therebetween.
